United States Patent Office

Des. 184,386
Patented Feb. 3, 1959

184,386

TUBE TESTER

Carl D. Volpe, Westbury, N. Y.

Application January 14, 1958, Serial No. 49,258

Term of patent 3½ years

(Cl. D26—1)

The single figure is a front perspective view of a tube tester, showing my new design. The back is conventional, and the opposite side is substantially a mirror image of the side shown.

I claim:

The ornamental design for a tube tester, as shown and described.
